UNITED STATES PATENT OFFICE.

LEE J. BLACK, OF BEAUMONT, TEXAS.

PUMP.

1,202,153.

Specification of Letters Patent. Patented Oct. 24, 1916.

Application filed October 21, 1915. Serial No. 57,063.

To all whom it may concern:

Be it known that I, LEE J. BLACK, a citizen of the United States, residing at Beaumont, in the county of Jefferson and State 5 of Texas, have invented certain new and useful Improvements in Pumps, of which the following is a specification.

This invention relates more particularly to the valve chests of pumps, and its object 10 is to provide a pump having a valve chest which is formed of a single casting removably mounted on the pump cylinder, and carrying all the valves of the pump, thereby obtaining certain advantages as will be 15 pointed out hereinafter.

The invention also has for its object to provide a valve chest of novel construction and improved means for securing the same to the pump cylinder.

20 In order that the invention may be better understood, reference is had to the accompanying drawings, in which—

Figure 1 is an elevation of the pump partly in section on the line 1—1 of Fig. 3; Fig. 2 is a cross-section of the valve chest 25 on the line 2—2 of Fig. 3; Fig. 3 is a plan view, with parts in section, on the line 3—3 of Fig. 2, and Fig. 4 is a horizontal section on the line 4—4 of Fig. 2.

30 Referring specifically to the drawings, 10 denotes the cylinder of the pump, the same containing a liner 11 in which the pump plunger 12 reciprocates. The pump illustrated is a steam pump, the steam engine cylinder being shown at 13, and the piston 35 of the latter being directly connected to the pump plunger rod 14. It is to be understood, however, that the invention is not limited to this type of pumps, as any other 40 suitable power and driving connections may be employed.

The pump cylinder 10 is provided with a valve chest 15 which carries all the valves of the pump and is entirely separate from 45 the pump cylinder and removably connected thereto. The pump cylinder is a single casting which is bolted to the cylinder over the end ports 16 and 17 thereof. The base of the valve chest has an encircling outstanding flange 18 which matches a flange 19 on 50 the cylinder. Bolts 20 passing through the flanges 18 and 19 secure the valve chest to the cylinder. Additional fastening means for the valve chest are also provided, the 55 same comprising a row of bolts indicated at 21, 22, 23, 24 and 25, respectively, the same

projecting from the base of the valve chest and being here threaded to screw into the cylinder wall. The outer ends of the last-mentioned bolts are threaded to receive nuts 60 26, and the latter, with the exception of the nut of the bolt 21, also serve to secure clamps 27 which hold down the valve covers 28 to be presently described.

The inlet chamber 29 of the cylinder 10 is 65 between the end ports 16 and 17 and has the usual intake. The valve chest 15 seats over this chamber.

The valve chest 15 has a top discharge chamber 30, provided with an outlet 31. 70 Beneath the discharge chamber, and separated therefrom by a partition 32, are four inlet chambers 33, 34, 35, and 36, respectively, separated from each other by a transverse partition 37 and a longitudinal partition 38 which cross and extend between the bottom wall 39 of the valve chest and the partition 32, and also between the side walls of the valve chest. These walls and partitions are all cast integral with the valve 75 chest.

The chambers 33 and 35 have inlet ports 40 which are in communication with the port 16, and the chambers 34 and 36 have inlet ports 41 which are in communication 85 with the port 17.

That portion of the bottom wall 39 of the valve chest which seats over the inlet chamber 29 of the cylinder 10 has valved inlet ports 42 establishing communication between said chamber and the respective inlet chambers 33, 34, 35 and 36. The valve of the chamber 33 is shown at 43, the valve of the chamber 34 at 44, the valve of the chamber 35 at 45 and the valve of the chamber 36 at 46.

In the partition 32 are valved ports 47 providing outlets for the inlet chambers 33, 34, 35 and 36 and establishing communication between said chambers and the discharge chamber 30. The outlet valve of the chamber 33 is shown at 48, the valve of the chamber 34 at 49, the valve of the chamber 35 at 50, and the valve of the chamber 36 at 51.

In operation, when the plunger 12 is traveling to the right, the pump takes in water from the inlet chamber 29 and through the valves 43 and 45, and discharges into the chamber 30 through the valves 49 and 51. 110 On the opposite stroke of the plunger, the pump takes in water through the valves 44

and 46 and discharges through the valves 48 and 50. The water entering the chamber 30 is discharged through the outlet 31. Above each valve, in line therewith, the top 5 of the valve chest 15 has an opening 52 which is closed by a cover 28 having a guide for the valve stem and also serving as an abutment for one end of the valve spring. The bolt 22 carries a clamp 27 for holding 10 the covers of the valves 43 and 44, the clamp for the covers of the valves 48 and 49 is carried by the bolt 23, the clamp for the covers of the valves 50 and 51 is carried by the bolt 24, and the clamp for the covers of the 15 valves 45 and 46 is carried by the bolt 25.

The bolts 21, 22, 23, 24 and 25 seat in the partition 38, the same being vertically apertured for this purpose. The bolts 21, 23 and 24 also pass through the discharge chamber 20 30, and in the latter, between the top thereof, and the bottom formed by the partition 32, are webs 53 which are apertured to house the bolts 23 and 24. From the side wall of the chamber 30 extends a web 54 25 which is apertured for the bolt 21. It will therefore be seen that where the bolts pass through the water chambers of the valve chest, they are completely covered and housed, which prevents the water or other 30 fluid from passing along the bolts and leaking out at the top. The bolts are also protected against corrosion.

In the operation of pumps it is a common occurrence, from one cause or another, for 35 the fluid end of the pump to crack, or the valves to cut around, especially when handling slush in drilling wells, the same containing much grit, and the valves are also liable to be cut by the sand in the fluid. In 40 either case, the destruction or ruin of a valve seat, in the old method of casting the valve chest integral with the pump cylinder, renders the entire valve chest and cylinder useless. However, by casting the valve chest in 45 one piece, separate from the cylinder, the cutting of a valve requires only a new valve chest, and the cracking of the cylinder would not destroy the valve chest. It will therefore be evident that the up-keep and 50 maintenance of the pump is considerably cheapened. With the valve chest and cylinder cast in one piece it is also impossible to observe the interior part of the casting, and note the natural casting defects, such as blow 55 holes, shrinkage, cracks, etc., but where the valve chest is cast separate, these defects are easily observed, as a complete view of the interior may be had. It is also possible to observe all ports, cored holes, etc., and to 60 determine whether there has been a shifting of cores, or any other trouble that would be likely to reduce the thickness of the metal in one place and add to the thickness in another. A further advantage of the present 65 design is that a uniform thickness of metal

may be provided for, doing away with any possibility of thinner sections cooling more rapidly than a thick section, and also eliminating the natural segregation of metal which cannot be detected beneath the casting scale, and if so detected will prove defective under actual use.

I claim:

1. A valve chest for pumps formed in one piece with a discharge chamber and a 75 plurality of inlet chambers separated by partitions, said inlet chambers having valved inlets and outlets, the latter opening into the discharge chamber, and fastening bolts for the valve chest passing therethrough and through one of the aforesaid partitions, certain of said bolts also passing through the discharge chamber, and said chamber having webs through which the last-mentioned bolts pass and in which they 80 are housed and shut off from the interior of the discharge chamber.

2. A valve chest for pumps formed in one piece with a discharge chamber and a plurality of inlet chambers separated by partitions, said inlet chambers having valved inlets and outlets, the latter opening into the discharge chamber, fastening bolts for the valve chest passing therethrough and through one of the aforesaid partitions, certain of said bolts also passing through the discharge chamber, and said chamber having webs through which the last-mentioned bolts pass and in which they are housed and shut off from the interior of the discharge 90 chamber, the valve chest also having openings in line with the aforesaid valved inlets and outlets, closures for said openings, and holding means for the closures carried by the aforesaid bolts.

3. A valve chest for pumps formed in one piece with a discharge chamber and a plurality of inlet chambers separated by partitions, said inlet chambers having valved inlets and outlets, the latter opening into the 100 discharge chamber, fastening bolts for the valve chest passing therethrough and through one of the aforesaid partitions, certain of said bolts also passing through the discharge chamber, and said chamber having webs through which the last-mentioned bolts pass and in which they are housed and shut off from the interior of the discharge 105 chamber, the valve chest also having openings in line with the aforesaid valved inlets and outlets, closures for said openings, and holding means for the closures carried by the aforesaid bolts.

4. A valve chest for pumps formed in one piece with a discharge chamber and a plurality of inlet chambers separated by partitions, said inlet chambers having valved inlets and outlets, the latter opening into the 110

discharge chamber, fastening bolts for the valve chest passing therethrough and through one of the aforesaid partitions, certain of said bolts also passing through the discharge chamber, and said chamber having webs through which the last-mentioned bolts pass and in which they are housed and shut off from the interior of the discharge

chamber, and a bolting flange on the base of the valve chest.

In testimony whereof I affix my signature in the presence of two witnesses.

LEE J. BLACK.
